US0D1067554S

(12) **United States Design Patent** (10) **Patent No.:** **US D1,067,554 S**
(45) **Date of Patent:** **** Mar. 18, 2025**

(54) **TAG APPLICATOR FOR ANIMALS**

(71) Applicants: **ALLFLEX AUSTRALIA PTY LIMITED**, Queensland (AU); **Allflex Europe SAS**, Vitre (FR)

(72) Inventors: **Benjamin Thomas John Wilkinson**, Queensland (AU); **Antonin Maurice Patrick Filippelli**, Albi (FR); **Quentin Serge Le May**, Albi (FR); **Bruno Philippe Jean Teychene**, Albi (FR)

(73) Assignees: **ALLFLEX AUSTRALIA PTY LIMITED**, Queensland (AU); **Allflex Europe SAS**, Vitre (FR)

(**) Term: **15 Years**

(21) Appl. No.: **29/810,575**

(22) Filed: **Oct. 6, 2021**

(30) **Foreign Application Priority Data**

Apr. 8, 2021 (EM) 008491476-0001

(51) **LOC (15) Cl.** **30-99**

(52) **U.S. Cl.**

USPC **D30/199**

(58) **Field of Classification Search**

(57) **CLAIM**

The ornamental design for a tag applicator for animals, as shown and described.

DESCRIPTION

FIG. 1 is a left side view of a tag applicator for animals; FIG. 2 is a right side view thereof.

FIG. 3 is a top view thereof.

FIG. 4 is a bottom view thereof.

FIG. 5 is a front view thereof.

FIG. 6 is a rear view thereof; and,

FIG. 7 is a perspective view thereof.

The broken lines depict portions of the tag applicator for animals, in which the design is embodied that are not considered part of the claimed design.

1 Claim, 7 Drawing Sheets
